UNITED STATES PATENT OFFICE.

ROBERT D. VALENTINE AND FREDERICK A. VALENTINE, OF MINNEAPOLIS,
MINNESOTA.

POWER-DRIVEN CULTIVATING MACHINE.

Application filed March 8, 1920. Serial No. 364,011.

To all whom it may concern:

Be it known that we, ROBERT D. VALENTINE and FREDERICK A. VALENTINE, citizens of the United States, residing at Minneapolis, in the county of Hennepin and State of Minnesota, have invented certain new and useful Improvements in Power-Driven Cultivating Machines; and we do hereby declare the following to be a full, clear, and exact description of the invention, such as will enable others skilled in the art to which it appertains to make and use the same.

Our invention has for its special object to provide an improved power-driven cultivating machine; and, to this end, our invention consists of the novel devices and combinations of devices hereinafter described and pointed out in the claims.

Our invention, in its preferred form, is illustrated in the accompanying drawings, wherein like notations refer to like parts throughout the several views.

Referring to the drawings:—

Fig. 1 is a plan view of our improved machine, some parts being removed and others broken away, the full lines showing the parts as they appear when the steering post is so connected up that its normal position is a central one parallel to the four wheels, when the four wheels are in line, and the dotted line positions show the result of swinging the steering post to the right;

Fig. 2 is a view similar to Fig. 1, but with more of the parts removed and the steering post shown connected up in such a way that its normal position will not be central when the four wheels are in alignment, but will stand at an angle to the median vertical plane of the machine;

Fig. 3 is a view in right side elevation looking at the parts as connected up and shown in Fig. 1;

Fig. 4 is a view chiefly in elevation looking in the same direction as in Fig. 3, but showing some of the parts on a larger scale, with some portions broken away and others sectioned;

Fig. 5 is a vertical section on the line 5—5 of Fig. 4;

Fig. 6 is a detail in plan of two of the parts shown in Fig. 4; and

Fig. 7 is another detail in plan showing one of the parts of Fig. 4 detached.

A suitable main frame 8 is supported by a pair of traction wheels 9 and a pair of 55 caster wheels 10. The axles of the caster wheels are each provided with a forwardly projecting crank arm 11; and these two crank arms 11 are pivotally connected, at their forward ends, by an adjustable rigid 60 cross tie 12. One of the axles of said caster wheels is also provided with a steering crank arm 13 to which the forward end of a rigid steering bar 14 is pivotally connected. This steering bar 14 extends rearward, 65 under the main frame 8, and is pivotally connected by a nutted bolt 15 to a sector 16 carried on the outer end of a crank arm 17 adapted to be rigidly but detachably secured by a set screw 18 to the lower end of 70 a hollow vertical shaft 19 forming part of an angular flanged hollow casting 20 to which the steering post 21 is adapted to be rigidly but detachably secured by a pair of heavy set screws 22, as best shown in Fig. 4. 75 The vertical shaft section 19 of the flanged casting 20 works in a suitable vertical bearing 23, cast integral with the main frame 8, near the rear end of the same, with its flange resting on the top of said bearing, as 80 best shown in Figs. 4 and 5. The part of said hollow casting 20, which serves as a socket to receive the lower forward end of the steering post 21, stands at an obtuse angle to the hollow vertical shaft portion 19 85 of said casting, so that when the steering post 21 is in working position, it will extend rearward and upward on a corresponding angle, as best shown in Fig. 3. At its upper or rear end, said steering post 21 is 90 provided with a socket casting 24 rigidly but detachably secured thereto by a suitable set screw 25, and to this socket casting 24 is centrally pivoted another socket casting 26 to which the handle bars 27 are rigidly 95 but detachably secured by suitable set screws 28. The handle bars of the steering post are, therefore, adapted to angular motion lengthwise of the steering post 21, for a purpose which will presently appear.

The numeral 29 represents a suitable tool head adapted to support and carry any desired number of detachable cultivating tools 30, and this tool head is pivotally connected to the main frame by a pair of drag bars 105 31, as best shown in Figs. 1, 2 and 3. The

pivotal connections between the ends of these drag bars 31 and the parts to which they are connected are of such a character that the tool head is free for vertical motion and also free for lateral motion, while maintaining parallelism with the tractor wheel shaft.

The numeral 32, as best shown in Figs. 2 and 3, represents what may be properly termed a shifting bar; and this bar 32 is pivoted to the main frame, at its forward end, in cross line with the forward pivotal connections of the drag bars 31 and equidistant between the two, or, in other words, at the cross center of the main frame—all three of these pivotal connections being directly to the rear of the traction wheel axle. At its rear end, the shifting bar 32 is pivotally connected to the tool head 29, either directly or indirectly, by a rigid link 33; and hence, it, of course, follows that, if the rear end of this shifting bar 32 be shifted laterally in either direction, it will move with it, laterally, the tool head 29 and the cultivating tools 30 carried thereby. This tool-shifting motion of said shifting bar 32 is secured from the handle bar of the steering post by means, which will now be noted. To this end, a vertical shaft 34 is mounted in the hollow vertical shaft 19 of the steering post casting 20 as a bearing, and has, at its lower end, a crank arm 35 rigidly but detachably secured thereto by a set screw 36, as best shown in Fig. 5, and the outer end of this crank arm 35 has slot, cross head and pin connection with said shifting bar 32, as best shown in Figs. 4 and 6. The slot in the bar 32 is marked with the numeral 37 and the nutted bolt, as best shown in Fig. 4, is marked with the numeral 38 and the cross-head with the numeral 38^a. The slot, of course, is to permit the necessary angular motion of the crank arm 35, notwithstanding the fact that the forward end of the shifting bar 32 is pivotally held against longitudinal motion.

The said shaft 34 has, at its upper end, another crank arm 39 rigidly but detachably secured thereto by a set screw 40, and the outer end of this top crank arm 39 is pivotally connected by an adjustable rigid connection 41 to the pivoted socket casting 26 of the handle bar, at a point eccentric to the pivotal center thereof, as best shown in Figs. 1 and 2. Said rod 41 is shown connected to said crank arm 39 by an angular clip 41^a and a nutted bolt 41^b. In virtue of these connections, it is, of course, obvious that when the handle bar receives angular motion lengthwise of the steering post 21, the vertical shaft 34 will be rocked; and hence its lower crank arm 35, by its slot and pin connection with the shifting bar 32, will move the rear end of the shifting bar laterally of the main frame of the machine, and, by

means of the rod 33, force the tool head 29 and the tools 30 laterally therewith to the extent of the angular throw of the rear end of the shifting bar 32. The parts may be proportioned to give any range of lateral throw desired.

As shown in the drawings the vertical central shaft 34 is screw-threaded, at its opposite ends, and provided with retaining nuts 42, as an additional security for holding the same, together with its cranks 35 and 39 in their proper working position, in respect to the hollow vertical shaft 19 of the steering post casting 20.

In virtue of the features of construction so far noted, it must be obvious that, by swinging the steering post 21 laterally,—permissible by the turning of the vertical hollow shaft portion 19 of its flanged casting 20 in the fixed vertical bearing 23 of the main frame,—the steering bar 14 will be moved forward or backward, according to which direction said steering post 21 may be laterally swung; and hence, it follows that the steering crank arm 13 on the axle of one of the caster wheels 10, will receive a corresponding angular motion, and through the cross-connected crank arms 11, both of the caster wheels will be correspondingly turned in an angular direction, as required to steer the machine in the direction desired, under the propelling action of the motor. For example, in Fig. 1, it has been assumed that it is desired by the operator to turn his machine toward the left; and he properly sets his caster wheels to secure this result by moving the steering post 21 toward the right, and thereby bringing the said steering post and steering connections and caster wheels into the dotted line position there shown.

As shown in Figs. 1, 3 and all of the other views, with the exception of Fig. 2, the steering bar 14 is connected to the sector 16 of the crank arm 17, carried at the lower end of the vertical hollow shaft 19 of the steering post casting 20, at such a point on said sector 16 that the steering post will be central or extend rearward on the median line of the main frame of the machine, when the four supporting wheels of the machine are in line with each other. Otherwise stated, the normal position of the steering post is assumed to be the central one, so that the operator will walk directly behind the center of the machine. The said sector 16, however, is shown as provided with a number of holes into which the rear end of said steering bar 14 may be secured; and, hence, it is possible to make the connection to said sector at such a point that the normal position of the steering post may be that shown in Fig. 2 of the drawings, when the four supporting wheels are in line with each other; and when this off-setting con-

nection is made, the operator, with his hands on the handle bars, can walk to one side of the machine, as may be desirable when the machine is straddling a row of corn or other plants to be cultivated.

Whether the connection between the steering bar 14 and the sector 16 be such as to have the steering post 21 central when the four supporting wheels are in line with each other, as shown in the main views, or at one side, as shown in Fig. 2, is immaterial to the action of the parts by which the cultivating tools are shifted laterally, whenever so desired, by the angular motion of the pivoted handle bar casting lengthwise of the steering post. The operator can always secure this lateral movement of the tool head and its tools by making the necessary angular movement of the handle bars, as shown, for example, in dotted lines in Fig. 2 of the drawings. Unless the operator makes the necessary effort to produce this angular motion of the handle bar, the handle bar will maintain a position parallel to the axle of the traction wheels at all points in the lateral movement of the steering post 21, as shown by dotted lines in Fig. 1 of the drawings.

It will, of course, be understood why this provided lateral motion of the tool head 29 and the cultivating tools 30, carried thereby, is desirable. Corn or other plants do not always set in a true line lengthwise of the road and, at different stages of the growth, the supporting wheels of the machine must travel at slightly different distances from the rows of plants, if the machine be traveling between two rows of plants; and hence, a lateral motion of the tool head and tools must be provided to avoid tearing up some of the plants, while, at the same time, being able to bring the adjacent cultivators into the most advantageous position for tearing out the weeds and throwing up the soil into the desired position, relative to the plants.

It should be obvious that the sector 16, with its plurality of holes, carried at the outer end of the crank arm 17 secured to the lower end of the vertical hollow shaft 19 of the steering post, is simply one convenient and preferred means for varying the angle at which the crank arm of the steering post may be connected to said steering bar, in order to vary the normal position of the steering post 21, in respect to the median line of the machine. Other substitute means could obviously be employed. For example, the crank 17 might be angularly adjusted on the vertical shaft of the steering post and the steering bar be longer and have a series of holes for the pivotal connection, or be made in two sections adjustably connected by a turnbuckle or slots and a clamping bolt.

In practice, the traction wheels 9 are adjustable lengthwise of their supporting axle to vary the width of the tread, as needed for adaptation to differently spaced rows of plants.

In practice, means will, of course, be provided for lifting the tool head 29 into an elevated position and there holding it, when the tools are not in use, as, for example, when traveling on the road, or turning around the end of a row of corn or other plants.

For the purpose of this case, the character of the power drive for the traction wheels 9 is a matter of indifference. In Fig. 1 of the drawings, however, an internal combustion engine 43 is shown mounted on the main frame, toward the forward end of the same, with its crank shaft extending lengthwise of the machine on the median line of the frame and having secured thereto an extension 44 on which is splined a friction disk 45, having peripheral contact with the profile face of a large friction disk 46 carried by and rigid with a countershaft 47, having thereon one member 48 of a train of gearing, including members 50 and 51 on another short countershaft 52 and a gear 53 fixed to the axle of the traction wheels 9. The members of this train of gearing are so proportioned, relative to each other, that the speed of the engine shaft will be properly reduced, with a corresponding increase of power, and take effect on the gear 53 fixed to the axle of the traction wheels for maximum predetermined speed. The speed can be further varied within the working range by shifting the small friction disk 45 lengthwise of its supporting shaft, so as to move the same radially inward or outward from the center of the large friction disk 46. The device for making this shift of said friction disk 45 is not shown, but, in practice, would be under control of the operator, through a connection extending to the operator's position at the handle bar. In practice, the large friction disk 46 is mounted so as to slide on the countershaft 47 and is subject to a toggle lever with an operating connection extending to within reach of the operator at the handle bar for throwing the said two disks 45 and 46 into and out of operative relation, at the will of the operator. In practice, there is also a connection to the throttle valve of the engine controllable by the operator at the handle bar. In practice, the train of gearing from the countershaft 47 to the axle of the traction wheels 9 includes a differential gear, so that either traction wheel can turn independent of the other.

What we claim is:—

1. The combination with a main frame, of a rear pair of tractor wheels and a front pair of caster wheels having separate axles

supporting said frame, a pair of cross-connected crank arms, one on each of the axles of said caster wheels, a horizontal steering crank arm on the axle of one of said caster wheels, a rearwardly extended inclined steering post pivoted to said frame for lateral swinging motion, a horizontal steering crank arm movable laterally with said steering post, and a rigid connection pivotally connecting said two steering crank arms, substantially as described.

2. The combination with a main frame, of a rear pair of tractor wheels and a front pair of caster wheels having separate axles supporting said frame, a pair of cross-connected crank arms, one on each of the axles of said caster wheels, a horizontal steering crank arm on the axle of one of said caster wheels, a rearwardly extended inclined steering post having a vertical pivot shaft mounted in a vertical bearing fixed to said frame and provided with a horizontal steering crank arm, and a rigid connection pivotally connecting said two steering crank arms, substantially as described.

3. The combination with the main frame of a power driven cultivating machine, of a tool head for carrying cultivating tools, drag bars pivotally connecting said tool head with said frame, a shifting bar pivoted to the main frame at its forward end and having its rearward end pivotally connected to said tool head, a steering post having a handle bar pivoted for angular motion lengthwise of the post, and rigid connections pivotally connecting said handle bar from a point eccentric to its pivotal center to the rear end of the shifting bar, whereby angular motion of the handle bar lengthwise of the steering post will shift the tool head laterally, substantially as described.

4. The combination with the main frame of a power driven cultivating machine, of a tool head, for carrying cultivating tools, drag bars pivotally connecting said tool head with said frame, a shifting bar pivoted to the main frame at its forward end and having its rearward end pivotally connected to said tool head, a steering post having its handle bar pivoted for angular motion lengthwise of the post, a vertical shaft on the main frame having a crank arm at its lower end with slot and pin connection to said shifting bar and having an operating crank arm at its upper end, and a rigid connection pivotally connecting said operating crank arm to said handle bar at a point eccentric to the pivotal center of the handle bar, substantially as and for the purposes set forth.

5. In a machine of the class described, the combination with a rearwardly extended inclined steering post having a hollow vertical pivot shaft mounted in a vertical bear-

ing fixed to said frame with connections for steering the machine by the lateral motion of said steering post and provided with a handle bar pivoted for angular motion lengthwise of the steering post, of a tool head with drag bars pivotally connected to the main frame of the machine, a shifting bar having its forward end pivoted to the main frame and its rear end pivotally connected to said tool head, a vertical shaft mounted in the hollow pivot shaft of said steering post and having at its lower end a crank arm with slot and pin connections to said shifting bar, and having in its upper end an operating crank pivotally connected by a rigid connection to said handle bar at a point eccentric to the pivotal center of said handle bar, all for cooperation, substantially as described.

6. In a wheeled cultivator, the combination with a main frame and a tool head, of drag bars pivotally connecting the tool head to the main frame with freedom for lateral swinging motion of the tool head and tools, a steering post pivoted to said frame adapted to be rotated for guiding said cultivator, a handle bar pivoted to said steering post for angular motion lengthwise thereof, and connections from said handle bar to said tool head, whereby the angular motion of said handle bar lengthwise of said steering post will shift the tool head and tools laterally, as desired.

7. In a wheeled cultivator, the combination with a main frame and a tool head, of drag bars pivotally connecting the tool head to said main frame with freedom for lateral swinging motion, a shifting bar pivoted to the main frame and having its rear end pivotally connected with said tool head, a steering post pivoted to said frame adapted to be rotated for guiding said cultivator, and a handle bar pivoted to said steering post for angular movement lengthwise thereof and provided with connections to said shifting bar, whereby said tool head and tools may be shifted laterally by the angular movement of said handle bar lengthwise of said steering post, substantially as described.

8. In a power-driven machine having a main frame supported by a rear pair of tractor wheels and a front pair of caster wheels, the combination with said main frame, of a steering post pivoted thereto for lateral swinging motion, and connections therefrom to said front pair of caster wheels for steering said machine by the lateral motion of said steering post and which connections include a steering bar and a crank arm on the steering post, and means for adjusting the angle at which the said crank arm and steering bar are pivotally connected, whereby the normal position of the

steering post may be in the median line of the machine or offset to one side of the machine, at will.

9. In a power-driven machine having a main frame supported by a rear pair of tractor wheels and a front pair of caster wheels, the combination with said main frame, of a steering post pivoted thereto for lateral swinging motion, and connections therefrom to said front pair of caster wheels, for steering the said machine by the lateral motion of said steering post, and which connections include a steering bar and a crank arm on the steering post having in its outer end a sector with a series of holes into which the rear end of the steering bar may be pivotally connected for varying the normal position of the steering post in respect to the median line of the machine.

10. A power-driven cultivating machine having in combination a pair of rear driving wheels, a pair of front caster wheels, a steering mechanism for angularly turning said front wheels, a laterally movable tool head, a pivot post structure, means connecting said pivot post structure to the steering mechanism, means connecting said pivot post structure to the tool head, and a controlling bar extending rearwardly from said pivot post structure and so connected therewith that angular movements thereof will control the steering mechanism, and having means thereon, the angular movement of which will control the movements of the tool head.

11. A power-driven cultivating machine having in combination a pair of rear driving wheels, a pair of front tractor wheels, a common axle passing between the rear driving wheels, steering mechanism for angularly turning the front wheels, a tool head laterally movable in parallelism with said axle, a pivot post structure, means connecting said structure to the steering mechanism, means connecting said structure to the tool head, a control bar connected to the pivot structure and angularly movable thereabout, said bar extending to the rear of the machine, means connecting said bar to the pivot structure whereby angular movements of the bar will control the steering mechanism, and means carried by the end of the bar and so connected to the pivot structure that angular movements of the same relative to said bar will move the tool head.

12. In a power-driven cultivating machine having a steering device and a tool head, a frame having a bearing member therein, a post member journaled in said bearing member and adapted to be connected to said steering device, and a second post journaled inside of said first mentioned post and adapted to be connected to said tool head.

13. The structure set forth in claim 12, and means connecting the first mentioned post to the steering mechanism.

14. The structure set forth in claim 12, and means connecting said second mentioned post to the tool head.

15. The structure set forth in claim 10, said pivot post structure comprising telescoped posts, one of which is connected to the steering mechanism and one of which is connected to the tool head.

16. A power-driven cultivating machine having in combination a frame, a pair of wheels turnable relatively thereto about vertical axes for steering said machine, a vertical shaft mounted in said frame, a tool bar, means rotatable about said shaft for turning said wheels, and means rotatable with said shaft for laterally shifting said tool bar.

17. A power-driven cultivating machine having in combination a laterally movable tool head, a single rearwardly extending steering post, a pair of handle bars extending horizontally adjacent the rear end of said post and pivoted thereto by a vertical pivot, and means for swinging the tool bar laterally when the handle bars are swung about said pivot relatively to said post.

18. A power-driven cultivating machine having in combination, a laterally movable tool head, a single rearwardly extending steering post, a pair of handle bars extending transversely of said post adjacent its rear end and pivoted thereto by a pivot extending substantially normal to the axis of said post and means for swinging the tool bar laterally when said handle bars are swung about said pivot relatively to said post.

19. A power-driven cultivating machine having in combination, a frame, movable steering wheels therefor, a movable tool head, a single rearwardly extended swingable post, a handle bar swingably mounted adjacent the rear end of said post, means for moving the steering wheel by swinging movement of said post, and means for moving the tool head by swinging movement of said bar.

20. A power-driven cultivating machine having in combination, a pair of guide wheels at the front of the machine turnable about vertical axes to steer the machine, a laterally shiftable tool bar, a member movable to turn said wheels, and a member movable to shift said bar, both of said members being movable about a common axis.

In testimony whereof we affix our signatures.

ROBERT D. VALENTINE,
FREDERICK A. VALENTINE.
